INTERNAL COMBUSTION ENGINE

Mario Gentili, Walla Walla, Wash.

Application July 27, 1932, Serial No. 624,964

2 Claims. (Cl. 123—67)

This invention relates particularly to that type of internal combustion engines known as two-cycle engines. The invention relates more particularly to the means for reducing the pressure in the cylinders thereof when the engine is idling or running at a reduced power; to means for controlling such pressure reduction; to means for supplying the fuel mixture to such engine; to means for controlling such fuel supply; and to means for coordinating the two said controlling means.

The object of the invention are to provide improved mechanism for controlling the compression pressure of the engine; for operating the pressure meter valve; for controlling the time for opening and closing said meter release valve, and for controlling the degree of such opening; for operating the fuel supply valve; for controlling the time for the opening of said fuel supply valve, and the degree of such opening; and for coordinating the action of said two time controlling means. A further object is to provide a cheap, simple and effective mechanism, easily inspected, adjusted and repaired, and which is thoroughly rugged and practical, whereby the two-cycle engine may be made more elastic in its operating conditions and whereby its many advantages may be made effective.

I attain these and other objects by the devices, mechanisms, and arrangements illustrated in the accompanying drawings, in which—

Fig. 1 is a vertical section of an engine made in accordance with my invention; Fig. 2 is a vertical section of a part thereof through the metering mechanism, drawn to a larger scale and showing the parts in the positions occupied thereby when the piston is at the lower end of its stroke and showing the adjustment of the control mechanism for full power or high speed; Fig. 3 is a similar view showing the parts adjusted for low power or idling speed; Fig. 4 is a vertical section of a part thereof through the fuel feed mechanism, showing the parts in the positions occupied thereby when the piston is at the lower end of its stroke, and showing the adjustment of the control mechanism for full power and high speed; Fig. 5 is a similar view showing the parts in the positions occupied thereby when the piston is approaching the upper end of its travel, at a point immediately preceding the cutting off of its fuel supply, and showing the adjustment of the control mechanism for low power or idling speed; Fig. 6 is a horizontal section of a single cylinder of such an engine, taken on the lines 6—6 in Figs. 2 and 4; and Fig. 7 is a

diagrammatic view of the fuel and combustion air supply means.

Similar numerals of reference refer to similar parts throughout the several views.

The engine comprises the usual construction of a cylinder 1, or series of such cylinders, having a head 2, and surrounded by a suitable cooling means, such as the water-jacket 3. The head is provided with a combustion chamber 4 and with a suitable spark plug 5. A piston 6 reciprocates in the cylinder 1 in the usual manner, and is connected to the crank 7 of the engine shaft 8 by the usual connecting rod 9. The shaft 8 drives the cam shaft 10, through the equal gears 11, indicated in dotted lines in Fig. 1, at the same rate of rotation.

The cylinder 1 is provided with an exhaust port 12 adjacent to the lower end of the stroke of the piston 6, and with a scavenger port 13 opposite thereto. The upper wall of the exhaust port 12 is slightly higher than the upper wall of the scavenger port 13, thus permitting the pressure in the cylinder to be lowered through the exhaust before the scavenger port is opened. The scavenger port 13 is connected by suitable passage 25 to the scavenger chamber 14, which is supplied with air under pressure from the scavenger manifold 15. The air in the scavenger manifold 15 may be supplied by any convenient means, not shown, and should have a pressure of from 5 to 25 lbs. per square inch, the higher the pressure the more rapid the action.

The upper surface of the piston 6 is shaped to have a downward inclined face 16 from a raised central ridge 17 and leading to the exhaust port 12 when the piston is at the lower end of its stroke, and a concave curved portion 18 leading from the said ridge 17 to the scavenger port 13 when the piston is in said same position, thus directing the scavenger air from the port 13 up towards the combustion chamber 4 and reversing permitting the burnt gases to pass out of the exhaust port 12 freely and easily.

Referring now to Figs. 2 and 3, it will be seen that I provide an air port 19. This port 19 is positioned with its center about one-quarter of the piston stroke down from the upper end thereof. The port 19 leads to a valve chamber 20. A meter valve 21 opens into the valve chamber 20 to open connection with the air passage 22. A three-way valve 23 is mounted in this passage 22, to permit air to pass out of the open port 19 or to be returned to the scavenger chamber 14 by the return by-pass pipe 25.

The valve 21 is operated by the following mech-

55

anism:—The camshaft 10 is provided with a suitably shaped cam 26 which raises a plunger 27 against the action of the spring 28. The plunger 27 is suitably mounted in the engine frame and is adapted to be reciprocated therein. A rod 29 is secured to the upper end of the plunger 27 and is provided with an operating wedge-shaped head 30 at its upper end. The valve 21 has a stem 31 extending out from the engine and this stem 31 is engaged by a spring 32 which always tends to close the valve 21 tightly on its seat, to close connection between the valve chamber 20 and the air passage 22. A control shaft 33 is mounted adjacent the cylinder head 2, parallel with the engine shaft 8, and operated by any suitable means but preferably by means of a foot lever controlled and actuated by the operator of the engine. This shaft 33 has an air control cam 34 thereon. This cam 34 operates a rocker lever 35, suitably mounted on a bracket 36, against the action of the spring 37. The contact between the cam 34 and the lever 35 may be adjusted by the contact set screw 38. The other end 39 of the lever 35 extends down to a point substantially in the extension of the axis of the valve stem 31 but removed therefrom and forms a back-stop for the head 30 above described. When the engine operator wishes the engine to idle, he turns the shaft 33 to bring the cam into the position shown in Fig. 3. In this position the cam 34 is furthest extended from the axis of the shaft 33 at its point of contact with the adjusting screw 38 of the lever 35, thus swinging the said lever 35 to its greatest extent, against the action of the spring 37, and bringing the back-stop 39 thereof closest to the valve stem 31. The head 30 of the rod 29 is positioned between the said back-stop 39 of the control rocker lever 35 and the outer end of the valve stem 31. A swinging roller 40 may be hung from the bracket 36 and positioned between the head 30 and the stem 31. When the piston 6 is close to the lower end of its stroke, the cam 26 begins to rise and push the plunger 27 (Fig. 3) which forces the wedge-shaped head 30 upward between the adjustable back-stop 39 and the valve stem 31 and therefore begins to open the valve 21. The further rotation of the shaft 10 therefore opens the valve 21 to its full extent and holds it open while the piston 6 is rising. As the piston 6 rises it drives out part of the clean air in the cylinder through the port 19, chamber 20, and passage 22, so long as the valve 21 remains open, thus preventing any compression of the air in the cylinder 1 until the said valve 21 has been closed. With a further rising of the piston 6 and corresponding rotation of the shaft 10, the cam 26 recedes from the plunger 27, which follows it down under the action of the spring 28, thus withdrawing the wedge-shaped head 30 from between the back-stop 39 and the roller 40 or the end of the stem 31, thus permitting the spring 32 to return the valve 21 to its seat and thus close the passage 22. Compression of the remaining air in the cylinder 1 begins at this point. The extreme moment when this valve 21 is thus closed is preferred to be such that the piston 6 will have traveled about three-fourths of its stroke upward.

When the engine operator causes the control shaft 33 to be rotated from the above-described position, of idling speed or low power, the back-stop 39 is moved further outward thus increasing the gap between it and the roller 40 or the valve stem 31, with the result that the wedge head 30 will rise further before it forces the valve 21

open, as above described, and therefore the valve 21 will remain closed longer and will close sooner than when the engine is idling (Fig. 3) and also, since the said space is increased, the extent that the valve 21 will be thus opened will be equally decreased. When the engine operator turns the shaft 33 into the extreme high speed position (Fig. 2) the valve 21 remains closed, or opens momentarily a very minute amount, and the engine compression, power and speed are therefore increased to the fullest extent, especially since the supply of fuel is correspondingly increased, as hereinafter described.

Referring now to Figs. 4 to 7, it is seen that a fuel port 41 is positioned in the cylinder 1 at a point slightly above that of the meter port 19 (Fig. 2) and to one side thereof (Fig. 6), at a position with respect to piston movement to be covered by that member during the firing period. The outer portion of the port passage is somewhat enlarged and is provided with the fuel supply fitting 42 secured therein. The fitting 42 is provided with an air supply passage and pipe 43 and a fuel supply passage and pipe 44 (Fig. 6) leading to the seat of the needle valve 45, and with an outlet passage 46 leading therefrom. A spray nozzle 47 is mounted in the end of the outlet passage 46 and extends to the port 41. The fitting 42 also has a cylindrical chamber 48 terminating in the needle valve seat. The needle valve 45 has a stem 49 extending out beyond the fitting 42. A flexible airtight gasket 50 is secured to the stem 49 of the needle valve 45, immediately at the rear thereof, and is held in the cylinder 48 by means of the tubular holder 51, fitting tightly in the chamber 48 and held therein by the head 52 which closes the chamber 48. A spring 53 is mounted around the stem 49, between the needle valve 45 and the head 52, and presses the said needle valve on to its seat to close the passages 43 and 44. The stem 49 is provided with a vertical slot 54 near its outer end, outside of the fitting 42.

The cam shaft 10 is also provided with a fuel-supply-operating cam 55. This cam is shaped to rise gradually from the shaft and, having attained its maximum height, to return sharply thereto again, as shown in Figs. 4 and 5. The cam 55 engages a roller 56, mounted on the plunger 57, to raise the said plunger against the action of the spring 58. An operating rod 59 is attached to the plunger 57 and extends upward therefrom. The rod 59 is provided with a wedge or inclined surface 60, on its outward side, adjacent its upper end. The upper end of the rod 59 passes through the slot 54 in the stem 49 of the needle valve. The fuel fitting 42 carries a bracket 61 which has an arm 62 extending therefrom, said arm 62 being adapted to form a fixed back-stop for the inner surface of the rod 59. The above-described control shaft 33 carries a fuel control cam 63. A rocker lever 64 is mounted on the bracket 61 and is provided with an adjustable contact screw 65 engaging the said cam 63. A spring 66 tends to hold the screw 65 in contact with the cam 63. The outer end of the lever 64 carries a swinging link 67 which is provided with a suitable roller 68 at its end. The roller 68 is positioned in the slot 54 of the stem 49 of the needle valve and adjacent the outer side of the rod 59, and is adapted to engage the wedge 60 when the rod 59 is raised. Thus it will be seen that when the rod 59 is raised by the cam 55 to drive the wedge 60 upward it will force the roller 68 against the end of the slot 54 and thus will force the stem 49 outward and will withdraw the 75

needle valve 45 from the ends of the passages 43 and 44, thus admitting air and fuel to the conically annular space surrounding the needle valve; and that such air and fuel will then mix and the fuel will be atomized and will pass into the cylinder 1 through the passage 46, nozzle 47 and port 41.

The fuel control cam 63 is in substantially the opposite phase from the meter cam 34 but both are mounted on, or formed on, the same controlled shaft 33. The operating cam 55 and the inclined surface 60 are so proportioned and positioned that the needle valve 45 will close quickly when the piston is between one-sixth and one-eighth of its stroke from the top, independent of the adjusted position of the control cam 63.

When the operator wishes to drive the engine at full power and speed, he turns the shaft 33 so that the cam 63 will raise the end of the lever 64 (Fig. 4), thus depressing the roller 68 and causing it to contact with the inclined surface 60 at an earlier moment, thus opening the valve 45 sooner, and also to a greater degree, than when the shaft 33 is turned to any other degree, and thus increasing the quantity of fuel vapor admitted into the cylinder 1. At this position of greatest power and speed, the valve 45 opens when the piston 6 has closed the exhaust port 12.

As the control shaft 33 is turned away from its maximum speed position, the roller 68 is raised slightly with the result that the valve 45 opens later and in lesser degree. The cams 26 and 55 on the operating cam shaft 10, the cams 34 and 63 on the control cam shaft 33, and the shape of the wedge surfaces 30 and 60 are so proportioned and shaped that the fuel supply needle valve 45 will not be opened until the meter valve 21 is closed, thus preventing the wastage of the fuel.

An air pump, indicated diagrammatically at 69 in Fig. 7, is operated by suitable means and supplies the proper volume of air for the vaporization of the fuel, at a pressure of from ten to forty pounds per square inch. The air is conducted from the pump 69 by the pipe 70 to the upper part of the container 71 whence it is conducted by the air pipe 43 to the needle valve 45. Also a fuel pump 72 is operated by suitable means and pumps the proper volume of liquid fuel from a supply tank (not shown) by the suction pipe 73 and delivers it by the pipe 74 to the lower part of the same container 71, whence it is conducted by the fuel pipe 44 to the needle valve 45. The amount of fuel in the container 71 is controlled by the float 75 and needle valve 76. A spring controlled by-pass valve 77 permits the return of the excess fuel.

By this means it is now apparent that clean air (or other non-explosive medium) positively supplants the foul gases; that the speed of action toward completely filling the cylinder with clean air, i. e. completely scavenging, depends only on the pressure of air when admitted to the cylinder; that further clean air is assured by the provisions for opening the valve 21 as the air will

then enter the top of the cylinder to assist purging, as above explained, stopping when the valve 21 closes; that when the valve 21 is timely closed it entraps the clean air in the cylinder when the proper predetermined volume occurs therein; and that the gas vapor is then added in proper and regulatable proportion to form an explosive mixture of the desired proportions, when the charge so formed is compressed and fired.

It is to be understood that many variations may be made in my improved engine without departing from the spirit of the invention as outlined in the appended claims.

Having, therefore, described my invention what I claim and desire to secure by Letters Patent, is:—

1. In an internal combustion engine, the combination with a cylinder, a piston, and an exhaust port adapted to be opened by the piston at the lower end of its stroke, of a scavenging port disposed with relation to the exhaust port to be opened by the piston later than that of the exhaust port, an air supply, a valve controlled metering port adapted to be closed by the piston at the upper end of its stroke, and having communication with said scavenging port, means to supply air under pressure from said supply jointly to said scavenging and said meter ports, means to timely actuate the valve of said meter port to admit air to the cylinder therethrough; meter the amount of air therein; and return the excess air to the air supply, means cooperable with said actuating means during the compression stroke to supply in proper portion an amount of fuel to the amount of metered air to form the required explosion, and means, including a spray nozzle adapted to be covered by the piston at the upper end of its stroke.

2. In an internal combustion engine, the combination with a cylinder, a piston, and an exhaust port adapted to be opened by the piston at the lower end of its stroke, of a scavenging port adapted to be opened by the piston later than that of the exhaust port, and positioned opposite said exhaust port, a valve controlled metering port adapted to be closed by the piston at the upper end of its stroke, and positioned diametrically opposite to said exhaust port, and having communication with said scavenging port when said valve is open, means to supply air under pressure jointly to said scavenging and said meter ports, a valve actuating mechanism adapted to actuate the valve of said meter port to admit air to the cylinder of said engine; meter the amount of air therein; and return excess air to the air supply, and a fuel feed mechanism coacting with said valve actuating mechanism during the compression stroke of said piston, to admit fuel to the retained air therein in required proportion, said fuel feed mechanism including a spray nozzle positioned to be covered for protection by the piston at the firing moment.

MARIO GENTILI.
